PIPE WRAPPING MACHINE

Leland S. Rosener, San Francisco, Calif., assignor
to The Paraffine Companies, Inc., San Fran-
cisco, Calif., a corporation of Delaware

Application August 4, 1930, Serial No. 472,858

8 Claims. (Cl. 242—11)

My invention relates to a pipe wrapping machine, and particularly to a machine in which the wrapping of many pipes may be effected with a minimum loss of time.

5 It is among the objects of my invention to provide a pipe wrapping machine in which pipes are wrapped with a strip of protective material; provision being made for applying an adhesive waterproof fluid to hold the wrapping in place, thus sealing the pipe with an impervious covering which is moisture and decay-proof.

10 Another object of my invention is to provide a pipe wrapping machine in which a plurality of pipes are successively moved into a wrapping position, so that while one pipe is being wrapped a completed pipe may be removed from the machine and replaced with another to be wrapped; the process of wrapping thus being a substantially continuous operation.

15 Further objects of my invention include the provision, in a pipe wrapping machine of the character described, of centralized controls for governing the operation of the machine, of quick-acting means for renewing the supply of wrapping material, and of improved means for applying an adhesive fluid to secure the wrapping on the pipe.

20 The invention possesses numerous other objects and features of advantage, some of which, with the foregoing, will be set forth in the following description of my invention. It is to be understood that I do not limit myself to this disclosure of species of my invention, as I may adopt variant embodiments thereof within the scope of the claims.

25 Referring to the drawings:

30 Figure 1 is a plan view showing the right hand portion of the pipe wrapping machine embodying my invention; and

35 Figure 2 is a similar view showing the left hand portion of the machine.

40 Figure 3 is a side elevation of the machine portion shown in plan by Figure 1; and

45 Figure 4 is a side elevation of portions of the machine shown in plan by Figure 2.

50 Figure 5 is a detail vertical sectional view of the tailstock mounting, taken in a plane indicated by the line 5—5 of Figure 4; the scale being larger than that of Figure 4 to disclose the construction more clearly.

55 Figure 6 is a vertical sectional view of the machine, taken in a plane indicated by the line 6—6 of Figure 2; the tailstock and carriage being shown in end elevation.

Figure 7 is perspective detail view showing the

fluid sprayer, taken in a direction indicated by the arrow 7 of Figure 6; portions of the sprayer are shown in section to disclose the construction.

5 Figure 8 is a vertical sectional view taken thru the tailstock; the plane of section being indicated by the line 8—8 of Figure 2.

Figure 9 is an end elevation of the headstock, taken in a direction indicated by the arrow 9 of Figure 1.

10 Figure 10 is a detail horizontal sectional view showing one set of the thrust rollers; the plane of section being indicated by the line 10—10 of Figure 11.

15 Figure 11 is a vertical sectional view taken thru the headstock; the plane of section being indicated by the line 11—11 of Figure 9.

20 Figure 12 is an end view of one of the pipe supports, taken in a direction indicated by the arrow 12 of Figure 11.

Figure 13 is a side view of one of the pipe centering studs, taken in a direction indicated by the arrow 13 of Figure 12; and

25 Figure 14 is a horizontal sectional view thru the same, taken in a plane indicated by the line 14—14 of Figure 13.

Figure 15 is a diagrammatic view of the control circuits.

30 In terms of broad inclusion, the pipe wrapping machine embodying my invention comprises a frame supporting a pair of rotors mounted in an adjustably spaced relationship. Each of the rotors are provided with journaled means for supporting the ends of a plurality of pipes, so that the pipes extend longitudinally between the rotors in a mutually spaced and parallel position. The pipe supporting means on one of the rotors is also preferably adjustable to assist in accommodating pipes of different sizes, and to effect the engagement of the supporting means.

35 A carriage, for carrying a strip of wrapping material, is mounted on the frame for movement in a path parallel with the axes of the pipes; and means, preferably electrically controlled, are provided for moving the carriage in either direction along the pipe. Means, also preferably electrically controlled, are provided for varying the speed of the carriage. The strip of wrapping material is preferably provided in a plurality of rolls, mounted on the carriage by a rotatable support, so that the supply of wrapping material

40 may be renewed quickly. Means, preferably mounted on the carriage, are also provided for emersing the strip in a heated waterproof adhesive fluid, and for spraying a similar fluid on the pipe to be wrapped.

Means, preferably electrically controlled, are provided for simultaneously rotating the rotors to successively move the pipes adjacent the path of movement of the carriage. Means are also provided for rotating the adjacently positioned pipe about its own axis, so that this rotation, together with a simultaneous movement of the carriage alongside the pipe, effects a spiral wrapping of the strip material on the pipe. Means are provided for varying the speed of rotation of the pipe being wrapped; and a varying of this speed, or a varying of the carriage speed, or both, may be used to control the angle of pitch of the spiral wrapping.

In the preferred form of my invention, a plurality of three pipes are arranged in their demountable positions between the rotors. While one of the pipes is being wrapped the rotors and remaining two pipes are free from rotation, and a completed pipe may be removed and replaced by another to be wrapped; this process being repeated so that the wrapping is carried on as a substantially continuous operation.

In greater detail, the pipe wrapping machine embodying my invention is supported by a frame 2 mounted on a suitable foundation 3. Arranged in fixed position near one end of the frame is a headstock 4, and movably mounted near the other end of the frame is a tailstock 6. Adjacent the outer end of the headstock 4 is an operator's platform 7, and a motor platform 8; the steps 9 and 11 permitting access to the platforms 7 and 8 respectively. This general arrangement is best shown in Figures 1 to 4 inclusive.

Referring principally to Figures 9 and 11, the headstock 4 is substantially in the form of a housing, having a demountable upper section 12 held secured by the bolts 13. Journaled in the headstock is a spool-shaped rotor 14. The journal for the rotor is provided by a plurality of rollers 16 circumferentially disposed about the peripheries of the rotor spool flanges. Twin sets of these rollers are journaled in pairs, in the rocker arms 17 pivotally mounted in lower portions of the headstock, to provide a cradle for the rotor 14. Another set of the rollers 16 is journaled in the upper section 12, and serves to bear on the top portions of the rotor to provide a closed journal.

It is to be noted that the rotor may be lifted out of its journal mounting by merely removing the demountable section 12. Endwise movement of the rotor 14 is prevented by the thrust rollers 18, journaled in the headstock and adapted to bear on both sides of the rotor spool flanges. The arrangement of these thrust rollers is indicated in Figure 11, and a detail showing of one set of these rollers is made in Figure 10.

Means are provided for rotating the rotor 14. This is preferably accomplished by an annular worm gear 19 mounted on one of the rotor spool flanges. A shaft 21, journaled in the lower portion of the headstock, carries a worm 22 meshed with the rotor gear 19; and rotation is imparted to the worm shaft 21 by an externally mounted shaft 23, thru the beveled gears 24. The shaft 23 is connected by the gears 25 to a power shaft 26, which is driven by a motor 27 thru a suitable speed reduction gearing 28. A magnetic clutch 29, interposed in the shaft 23, serves to control the rotation of the rotor; and since the speed of rotation of the rotor is not rapid, it may readily be adjusted to a predetermined angular position.

Means are provided on the rotor 14 for rotat-

ably supporting the ends of a plurality of pipes 31 to be wrapped. A plurality of shafts 32, three being shown, are journaled in the rotor 14 in the rotor spool flange bearings 33; these shafts being equally spaced about a circle concentric with the rotor axis, so that when the rotor is rotated the shafts, and consequently the pipes 31, will follow a predetermined circular path. The forwardly projecting ends of these shafts, those ends which are directed to the tailstock 6, are provided with means for engaging the pipe ends; and the rearwardly projecting ends of the shafts are provided with a clutch drive. This drive is effected by a shaft mounted loosely journaled gear 34, held against axial movement by a shaft fixed collar 38.

Suitable clutch means 37 are provided on the loose gear 34; and a clutch collar 38, slidably mounted for rotation with the shaft 32, is adapted to engage the clutch means 37 for locking the loose gear and shaft for rotation together. A shaft fixed collar 39 serves to limit the outward movement of the clutch collar 38. The clutch is preferably actuated by manually operated means. For this purpose, a hand lever 41 is pivoted on the rear exposed face of the rotor 14. A split ring 42, engaging an annular groove formed in the clutch collar 38, is pivoted in a frame portion of the hand lever 41.

By this arrangement, the clutch may be optionally engaged or disengaged at the will of an operator; and since the rotor 14 moves comparatively slowly, this operation may be readily effected either when the rotor is stationary or when it is being rotated. This permits any one of the journaled pipe supporting means, and consequently any one of the pipes 31, to be rotated at any time. Rotation is imparted to the loose gears 34 by a master gear 43 mounted for rotation on a shaft 44, having one end journaled in the frame 2 and the other end journaled in an axial aligned rotor fixed journal 46.

Rotation of the master gear shaft 44 is effected by the drive shaft 26 thru a pair of speed change transmission mechanisms. The gears 47 connect the master gear shaft 44 to a frame journaled shaft 48 carrying a series of gears 49. These gears are adapted to be optionally engaged by a series of shiftable complementary gears 51 slidably mounted for rotation on a frame journaled shaft 52. A frame mounted hand lever 53 provides a convenient means for shifting the shiftable gears 51. The extended shaft 52 also carries a shiftable clutch sleeve 54 optionally engageable with either of a pair of gears 56 and 57 loosely mounted on the shaft 52. These loose gears are meshed with a pair of connected gears 58 mounted on a frame journaled jack shaft 59. A frame mounted hand lever 61 provides a convenient means for shifting the shiftable clutch sleeve 54.

Connection with the drive shaft 26 is completed thru a gear 62 mounted for rotation with the gear 51, and a gear 63 loosely mounted on the drive shaft and meshed with the gear 62. A magnetic clutch 64 interposed between the loose gear 63 and the drive shaft 26 serves as a control for completely cutting off the drive to the speed change transmissions. It has been found convenient to choose the gear ratios in the transmissions so that the speed of rotation of the pipe supporting means, and consequently the pipes, may be varied thru speeds ranging from say 5 to 50 R. P. M.; this range being conveniently stepped thru the six speed changes provided.

The journaled pipe supporting shafts 32 are provided with means for readily engaging the ends of the pipes 31 to be wrapped. Referring to Figure 11, two different types of engaging means are shown. The projected end of the upper pipe supporting shaft 32 is shown carrying a removable collar 66 mounted for rotation with the shaft. A conical cap 67 is fixed on the collar, and serves to engage the end of a pipe. Due to its conical shape this engaging means automatically centers the pipe, and is preferably used for the smaller sized pipes.

For the larger diameter pipes, the engaging means shown on the other supporting shaft is preferably used. A collar 68 is demountably arranged for rotation with the shaft 32, and a face plate 69 is fixed on the outer end of the collar. A series of radial slots 71 are provided in the face plate, and a beveled stud 72 is adjustably mounted 20 in each slot. The stud is held slidably adjustable by a ribbed washer 73 and bolt 74. As shown in Figure 12, a series of concentric circles 76 are inscribed on the face plate to assist in setting the studs to center the pipe; these guide circles 25 are shown marked for pipes ranging in diameter from 18 to 36 inches. When the studs are adjusted they engage the inner rim of the pipe.

The other ends of the pipes to be wrapped are held by the tailstock 6. Except for certain details, the tailstock is of substantially the same construction as the headstock 4; and where substantial duplications in construction exist, these elements are similarly designated in both headstock and tailstock. Instead of being fixed on the frame 2 however, as is the headstock, the tailstock 6 is movably mounted. This is effected by providing a pair of rails 11 on the frame 2, and mounting the tailstock on the rails by suitable wheels 78; the brackets 79 being mounted on the tailstock to slidably engage the frame 2 for added stability.

Referring principally to Figures 5 and 8, movement of the tailstock 6 along the rails 11 is controlled by a hand crank 80 conveniently positioned at the outer end of the tailstock. The crank is mounted on a shaft 81 journaled in the tailstock and carrying a worm 82 meshed with a worm gear 83. The worm gear is mounted on a shaft 84, also journaled in the tailstock, carrying a spur gear 86 meshed with a rack 87 fixed on the frame 2. By this arrangement, it is apparent that a rotation of the crank 80 will impart a movement to the tailstock along the rails 11. This adjustment of the tailstock position permits the machine to accommodate pipes of various lengths; and the reduction in the gearing of the tailstock moving means is sufficient to hold the tailstock against movement after being set in a selected position.

Means are provided on the tailstock rotor for supporting the pipes 31. As best shown in Figure 8, a plurality of shafts 88 are slidably mounted in the journals 89 formed in the inner flange of the tailstock rotor spool. The shafts are held against rotation about their own axis by the shaft keys 91; and are spaced about the tailstock rotor in the same manner that the shafts 32 are spaced about headstock rotor. Thus, the pipes 31 extend longitudinally between the headstock and tailstock in a mutually spaced and parallel relationship.

The pipes 31 are held by the slidable shafts 88 by means of suitable engaging means; and these means may conveniently be of the same general type as those described in connection with the headstock. In case of the tailstock engaging means, however, rotatable means are provided.

In one type, the cone-shaped cap 67 is mounted to freely run on the ball bearing 92; and in the other type, the face plate 69 is mounted to freely rotate on the bearing 93.

Means are provided for extending and retracting the shafts 88 to permit engagement of the engaging means with the pipes 31, and also assist in accommodating various lengths of pipes. A flanged sleeve 94 is journaled in the bearing 95 formed in the outer flange of the tailstock rotor spool, and is held against endwise movement by a sleeve fixed collar 97. The rearwardly projecting end 98 of the shaft 88 is threaded into the sleeve 94, and a hand wheel 99 is secured on the outer end of the sleeve 94 to provide means for actuating the slideable shaft 88. By this arrangement, a plurality of pipes 31 may readily be mounted in, or demounted from, the supported position between the headstock 4 and tailstock 6.

Means are provided for rotating the tailstock 20 rotor simultaneously with the headstock rotor. The shaft 23, which extends thru the headstock gear box 101, continues along the length of the machine supported by the frame brackets 102. A portion of the shaft 23, adjacent the tailstock 25 6 and passing thru the tailstock gear box 103, is provided with a keyway 104. This keyway is slidably engaged by the keyed gear 106, corresponding to one of the gears 24 in the headstock gear box 101. This permits the tailstock rotor to be rotated without interfering with the tailstock movement.

Means are provided for covering the pipes with a helical wrapping; and means are also provided for adhesively securing the wrapping to provide a protective covering which is moisture and decay-proof. A portion of the frame 2 supports a pair of rails 107 running along the length of the machine, and extending parallel with the pipes 31. A carriage 108, provided with suitable wheels 109 for travel along the rails 107, is adapted to move back and forth alongside the pipes; the path of movement of the carriage being, of course, parallel with the axis of the pipes.

Movement, in either direction, is imparted to the carriage by a downwardly projecting finger 111 engaging an endless chain 112 running in the channels 113 provided between the rails 107. This arrangement is best shown in Figure 6. Referring particularly to Figures 1 and 2, the chain 112 runs over a pair of spaced sprockets 114 mounted on the frame 2. One of these sprockets is loosely journaled in a pair of adjustable bearings 116; this adjustment providing means for tensioning the drive chain 112. The other sprocket is fixed 55 for rotation on a frame journaled shaft 117.

Means are provided for running the carriage drive chain in either direction. A beveled gear 118 is mounted on the sprocket shaft 117, and meshes with a pair of beveled pinions 119 mounted on a frame journaled shaft 121. Another shaft 122 is journaled in the frame 2, and has loosely journaled thereon a pair of gears 123 meshed with a complementary pair of gears 124 mounted for rotation with the pinion shaft 121. Either of the loose gears 123 may be optionally locked for rotation with their journal shaft 122 by means of a pair of magnetic clutches 126 interposed between the shaft and the loose gears.

Means are also provided for varying the speed of the carriage drive chain 112. For this purpose an ordinary Reeves speed change is preferably used, comprised essentially of a twin pair of separable cone pulleys 127 between which a V-shaped belt 128 runs. A low-speed reversible motor 129 runs.

conveniently provides a means for controlling the spread of the cone pulleys 127 to vary the speed. One of the shafts 131 of the speed change is connected to the shaft 122 of the traverse mechanism 5 by a suitable chain drive 132; and the other shaft 133 is connected with the drive shaft 28 by a suitable chain drive 134.

Means, carried by the movable carriage 108, are provided applying a protective covering on 10 the pipe. Referring principally to Figure 2, a tank 136, for holding a supply of suitable waterproof adhesive fluid, is mounted on the carriage to swing about a suitable pivot 137. Means for 15 adjusting the angular position of the tank 136 18 is provided by a hand wheel 138 conveniently arranged on an operator's platform 139 of the carriage 108; the steps 140 permitting access to this 20 platform. Suitable gears 141 and a shaft 142 co-operating with a segment gear 143 on the tank 25 furnish means for swinging the tank about its pivot when the hand wheel 138 is turned. The reduction in the gearing is sufficient to prevent further movement of the tank after it has been 30 set in a preselected position.

25 A bracket 144 is secured on the rear of the tank 136, and carries the spools 146 secured on a shaft 147. A plurality of supply rolls 148 of a 35 wrapping strip 149 are removably journaled, preferably in pairs, about the peripheries of the supporting spools 146 and between the flanges thereof. The strip 149, which may be of any suitable 40 wrapping material such as a fibrous strip, is run off the upper positioned rolls, as shown in Figures 2 and 7; and when the material on these rolls is 45 depleted the spools may be rotated to bring up a new set of rolls, thus preventing loss of time in renewing the supply of wrapping material. A spring pressed catch 151 is adapted to engage 50 suitable recesses 152 in one of the spools, and serves to hold the supporting spools in a given 55 position.

As the strip material 149 is drawn off the upper roll, it is threaded through a frame 153 journaled 45 on the bracket 144. A counterweight 154 operates to rotate the frame 153 for retarding the strip movement. The strip 149 then passes under 50 a roller 154, over a roller 155, both mounted on the top of the tank 136, and then is directed under a roller 157 mounted within the tank. A rack 55 rod 158, slidable in a tank mounted guide tube 159 provides a mounting for the tank roller 157. Adjustment of the position of this roller within the tank is effected by a suitable gear arrangement, cooperating with the rack rod 158, operated 60 by a chain drive 161 and hand crank 162.

As the strip 149 emerges from the tank it passes over an adjustable roller 163 mounted on the 65 guide tube 159 on a suitable bracket 164. After passing off this roller, the strip is wrapped on one of the pipes 31, viz., that pipe which has been 70 rotated by the rotors 14 into a position adjacent the path of carriage 108. If it is desired not to pass the strip 149 into the tank 136, the strip may follow a course, indicated by the dotted 75 line 166, from under the roller 154 directly over the adjustable roller 163 and then to the pipe to be wrapped.

A suitable waterproof adhesive, such as a 70 bituminous material, is placed in the tank 136 to coat the strip. The material is kept in a heated fluid state by the heater tubes 167 extending into the tank. The burners 168, fed by a suitable 75 source of fuel 169, are positioned to discharge their flames into the heater tubes. This heating process permits the bituminous fluid to readily

penetrate the submerged fibrous strip. As a result, the strip is saturated and coated, and is in a condition to adhere to the pipe when it is applied as a wrapping.

Means are also provided for applying a coating 5 of the adhesive material on the pipe prior to the wrapping. This is preferably effected by a suitable sprayer mounted on the carriage 108. A pair of standards 171 are arranged on the carriage, one on each side of the pivoted tank 136. The upper portions of these standards are bent 10 forward, and are connected by a journaled cross bar 172. A pair of arms 173 are slidably mounted 15 for adjustment on the cross bar 172, and carry a cylindrical chamber 174 between their forward ends. The chamber 174 is eccentrically welded 20 on an inlet tube 176 and on an outlet tube 177, both mounted on the forward ends of the arms 173 for limited rotation therein.

The adhesive fluid from the tank 136 is fed 25 to the inlet tube 176 of the chamber 174, through a flexible conduit 178, by a suitable pump 179 located in the tank. A motor 181, driving 30 through a reduction gear 182, operates the pump. In order to function as a sprayer, the chamber 25 174 is provided with a series of slots or discharge orifices 183. A handle 184, fixed on the chamber 174, offers a means for rotating the chamber about its eccentric journal to adjust the position of the discharge orifices 183. A flexible conduit 35 186, communicating with the outlet tube 177 of the spray chamber 174, discharges back into the tank 136, and provides an overflow for the chamber.

Since the spray chamber 174 is supported by 40 the slideable arms 173, it may be extended or retracted to permit adjustment relative to the adjacently positioned pipe. To facilitate this adjustment, means are also provided for swinging the arms 173 about the axis of the cross bar 172. 45 A handle bar 187 is mounted on one end of the cross bar, and is restricted in its movement by a guide bracket 188 mounted on one of the standards 171; a counter balance 189 secured on the cross bar 172 operates to hold the spray chamber 174 in a selected position.

Another spray chamber 190 is preferably provided adjacent the chamber 174. This chamber is similar to the one just described, and is connected with the tank in substantially the same 50 manner; duplicate elements of construction being similarly designated in both spray chamber mountings. Instead of being mounted on the cross bar 172, however, the second chamber 190 is mounted on a tube 191 rotatable about the 55 cross bar. A handle bar 192 secured on the end of the tube 191 is arranged similar to the handle 187 of the cross bar, and serves to separately swing the spray chamber 190 about the axis of the cross bar 172; a counterweight 193 being 60 provided to hold the second chamber in adjusted position. The journal mounting of the spray chambers 174 and 190 provides means for making a final adjustment to accurately position the discharge orifices 183 relative to the pipe being sprayed; and the eccentric arrangement of the chambers insures ample space for fluid flow to the orifices.

Means are also provided for applying a final 70 covering of suitable material, such as a strip of kraft paper 194. A roll 195 of this material is pivotally mounted for adjustment on the carriage 108, and a suitable brake band 196 suspending a weight 197 serves to tension the strip as it is peeled off the roll. The kraft paper roll is ar- 75

ranged on the carriage, preferably adjacent the carriage operator's platform 139 for convenience, so that this material will be wrapped as a final covering over the bituminous saturated fibrous 5 wrapping.

The major controls for the machine are preferably located in two centralized positions; viz., on the frame mounted operator's platform 7 adjacent the headstock 4, and on the operator's platform 139 of the carriage. A switch board 198, conveniently arranged on the frame platform 7, is provided with suitable control switches; and a second switch board 199, conveniently arranged on the carriage platform 139, is also provided 10 with suitable control switches. In describing the control circuit for the machine the following abbreviated terms will be used to define the previously described magnetic clutches. The clutch 64 will be called a transmission clutch, and the clutch 29 will be termed a rotor clutch. One of the carriage drive clutches 126 will be called a forward clutch, and the other will be termed a reverse clutch.

Referring particularly to the control circuit, shown diagrammatically in Figure 15, the electric energy is taken from the lines 201 and 202 communicating with a suitable source of direct current. The forward clutch energizing coil 203 is connected at one end to the line 202, and is 15 connected at the other end to a switch arm 204 of a two-pole magnetic contactor generally designated 206. The contact element 207 of switch arm 204 is connected to the line 201, so that when the contactor is closed the coil 203 is energized and the forward clutch operated to drive the carriage 108 to the left as shown in Figures 1 and 2.

The other switch arm 208 of the contactor 206, is connected to one end of the contactor solenoid 209 having a plunger 211 operatively connected 20 to the switch arms 204 and 208 of the contactor. The other end of the contactor solenoid is connected to line 202 through the stop buttons 212 and 213, mounted on the carriage platform switch board 199 and frame platform switch board 198 respectively. A start button 214, mounted on the carriage switch board 198, is connected between the switch arm 208 and the line 201; and the contact element 216 of switch arm 208 is also connected to the line 201.

When the start button 214 is pushed, the circuit through the solenoid 209 is completed and the plunger 211 is actuated to close the contactor and engage the forward clutch. At the same time, the solenoid circuit is completed through 55 the switch arm 208 to hold the contactor closed after the start button is released. Upon pushing either of the stop buttons 212 or 213, however, the solenoid circuit is broken and the contactor is opened to disengage the forward clutch.

In order to prevent an accident, should the operator fail to stop the carriage, an automatic limit switch 217 is interposed in the solenoid circuit. This switch is shown in mounted position on the machine frame in Figure 2. An arm 60 218 projecting downwardly from the carriage 108 is positioned to engage and open the limit switch 217 before the carriage reaches the end of its track.

The reverse clutch energizing coil 219 is connected across the lines 201 and 202, and is controlled by a contactor 221 in a manner similar to the forward clutch coil 203. The start button 222 for the contactor 221 is mounted on the carriage switch board; and a reverse limit switch 70 75 223 is connected in a manner similar to the for-

ward limit switch 217. This switch mounting is shown in Figure 1, and is positioned for engagement by the carriage arm 224.

To prevent accident, should the operator push the start buttons for both forward and reverse clutches at the same time, or push one while the contactor of the other is closed, a mechanical interlock is provided between the contactors 206 and 221. This interlock is indicated at 226, and may be of any standard or well known type; the 10 interlock operating to prevent both contactors being closed at the same time.

The transmission clutch energizing coil 227 is connected across the lines 201 and 202, and controlled by a contactor 228 in a manner similar 15 to the forward clutch coil 203 except that in this case no limit switch is included. The start button 229 for the contactor 228 is mounted on the carriage switch board 199 as were the others.

The rotor clutch energizing coil 231 is also connected across the lines 201 and 202, and is controlled by a contactor 232. In this case, however, the contactor solenoid switch is omitted so that the contactor is closed only when a start button is pushed. Two start buttons 233 are provided, connected in parallel; one on the carriage switch board 199, and the other on the frame switch board 198. This arrangement permits either the operator on the frame platform 7, or the operator on the carriage platform 139 20 to rotate the rotors and move the pipes into the wrapping position.

The connections to various motors in the machine are now shown, since these are made in the usual manner. The control switches for the 35 reversible motor 129 of the carriage speed change, and the fluid pump motor 181 are mounted on the carriage switch board; while the control switch for the main drive motor 27 may be located at any convenient or advantageous position.

Operation: Considering that the carriage 108 is positioned at the head end of the machine adjacent the headstock 4, that the main drive motor 27 is running, and that all the clutches are 45 disengaged, a plurality of pipes 31 are mounted in position between the headstock and tailstock. The frame platform operator shifts the transmission gears, by means of the shift levers 53 and 61; and the carriage platform operator pushes his 50 start button 229 to engage the transmission clutch 64 for completing the drive to the clutch means 37 of the pipe supporting shafts.

An operator, preferably the frame platform operator, then pushes his start button 233 to engage the rotor clutch 29 and rotate the rotors 14; thus causing the pipes to move orbitally about the rotor axis. When one of the pipes 31 has been rotated into position adjacent the carriage 108, the operator releases the start button to 60 disengage the rotor clutch.

The carriage operator then swings the tank 136, by means of the hand wheel 138, until the proper angle is made with the pipe to be wrapped. Considering that the adhesive fluid is being heated, and that the strips 149 have been threaded through the carriage, the strips are secured to the pipe end by any suitable means.

Having adjusted the carriage speed change by rotation of motor 129, the carriage operator 70 pushes his start button 214 to engage the forward clutch and start the carriage moving along the pipe; at the same time, the frame platform operator throws in the clutch sleeve 38 of the pipe being wrapped by means of the lever 41. The 75

combined movements, viz., the revolution of the pipe and the linear travel by the carriage, serve to apply the strips 149 in a spiral wrapping.

As the wrappings start on the pipe, the carriage operator starts the pump motor 181 to spray the fluid on the pipe; the spray chambers 174 and 190 having previously been adjusted to position their discharge orifices 183 adjacent the point where the strips 149 start engagement with the pipe.

Two strips 149 are shown for purposes of illustration; it being obvious that one, or more than two may be used. In the present instance, two layers of the wrapping strip 149 are applied, one spiral over the other. After the wrapping has proceeded a short distance, the final covering of kraft paper 194 is started on the pipe, and the wrapping then proceeded until the pipe is completely covered. If it is desirable to change the pitch of the spiral wrappings, this may be accomplished by either varying the speed of the carriage, or the speed of rotation of the pipe being wrapped, or both; the angle which the strips make with the pipe being varied in accordance by turning the hand wheel 138.

After the pipe is covered, the carriage operator pushes his stop button 212 to disengage the forward and transmission clutches and stop both movement of the carriage and rotation of the pipe. The strips 149 are then cut, and the operation continued until the pipe is covered with the kraft paper 194. After cutting the paper strip, the carriage operator pushes the start button 222 to engage the reverse clutch and move the carriage back to the starting position; the gear ratios in the reverse mechanism permitting a quick return.

In the meantime, the frame platform operator again pushes his start button 233 to rotate the rotors and move a new pipe into the wrapping position. The above cycle of the wrapping operation is immediately started to wrap the new pipe. While the second pipe is being wrapped, the completed pipe is removed from its position and replaced by a new one; the complete operation as described being repeated so that the wrapping is effected as a substantially continuous operation.

In the machine illustrated and described three pipes are shown demountably positioned between the rotors, but it is to be noted that a less or greater number may be so arranged. In the form shown, since there are three positions of rest in a complete revolution of the rotors, it is convenient to remove the wrapped pipe in one position of rest, and place a new pipe in that mounting in another position of rest. By arranging suitable skid ways adjacent the machine the new and wrapped pipes may be conveniently directed to and away from the machine.

I claim:

1. In a pipe wrapping machine, means for rotatably supporting a plurality of pipes, a carriage for wrapping material, means for moving the supporting means to position each pipe successively adjacent the carriage and at a discharge position, means for revolving the adjacently positioned pipe and moving the carriage in time therewith to effect a spiral wrapping thereof, and means for effecting the recovery movement of the carriage while the supporting means moves the wrapped pipe to the discharge position.

2. In a pipe wrapping machine, a headstock, a rotor journaled in the headstock, a series of shafts journaled in the rotor for rotatably sup-

porting the ends of a plurality of pipes, a gear on each shaft, a central gear meshed with each of said shaft gears, means for rotating the rotor to move the pipes into and out of a wrapping position, means for rotating the central gear to revolve the pipes about their own axis, and means for applying a wrapping material to the pipe in said wrapping position.

3. In a pipe wrapping machine, a headstock, a rotor journaled in the headstock, a series of shafts journaled in the rotor for rotatably supporting the ends of a plurality of pipes, a gear journaled on each shaft, a central gear meshed with each of said shaft gears, means for rotating the rotor to move the pipes into and out of a wrapping position, means for rotating the central gear to rotate the shaft gears, clutch means for locking a selected shaft gear to its shaft for revolving a selected pipe about its own axis, and means for applying a wrapping material to the pipe in said wrapping position.

4. In a pipe wrapping machine, a pair of rotors, means journaled on said rotors for supporting a plurality of pipes therebetween, a movable carriage for wrapping material, driving means for the rotors, electrically controlled means interposed in the driving means for rotating the rotors to successively position the pipes adjacent the path of movement of said carriage, means for revolving the adjacently positioned pipe, electrically controlled means for moving the carriage to apply the wrapping material on the revolving pipe, and electrically controlled means for reversing the direction of movement of said carriage.

5. In a pipe wrapping machine, a pair of rotors, means journaled on said rotors for supporting a plurality of pipes therebetween, a movable carriage for wrapping material, driving means for the rotors, electrically controlled means interposed in the driving means for rotating the rotors to successively position the pipes adjacent the path of movement of said carriage, means for revolving the adjacently positioned pipe, means for varying the speed of rotation of said adjacently positioned pipe, electrically controlled means for moving the carriage to apply the wrapping material on the revolving pipe, means for varying the rate of movement of the carriage, and electrically controlled means for reversing the direction of movement of said carriage.

6. In a pipe wrapping machine, a pair of rotors, means journaled on said rotors for supporting a plurality of pipes therebetween, a movable carriage for wrapping material, means for rotating the rotors to successively position the pipes adjacent the path of movement of said carriage, a magnetic clutch interposed in said rotating means for controlling the rotation of said rotors, means for revolving the adjacently positioned pipe, and means for moving the carriage to apply the wrapping on the revolving pipe.

7. In a pipe wrapping machine, a pair of rotors, means journaled on said rotors for supporting a plurality of pipes therebetween, a movable carriage for wrapping material, means for rotating the rotors to successively position the pipes adjacent the path of movement of said carriage, a magnetic clutch interposed in said rotating means for controlling the rotation of said rotors, means for revolving the adjacently positioned pipe, a magnetic clutch interposed in said revolving means for controlling the rotation of the adjacently positioned pipe, and means for moving the

carriage to apply the wrapping on the revolving pipe.

8. In a pipe wrapping machine, a pair of rotors, means journaled on said rotors for supporting a plurality of pipes therebetween a movable carriage for wrapping material, means for rotating the rotors to successively position the pipes adjacent the path of movement of said carriage, a magnetic clutch interposed in said rotating

means for controlling the rotation of said rotors, means for revolving the adjacently positioned pipe, means for moving the carriage to apply the wrapping on the revolving pipe, means for reversing the direction of movement of said carriage, and a magnetic clutch connected with said reversing means for controlling the reversal of the carriage movement.

LELAND S. ROSENER.
